UNITED STATES PATENT OFFICE

AUGUSTINE H. MASSEY, OF STRATFORD, CONNECTICUT, ASSIGNOR TO COLUMBIA PHONOGRAPH COMPANY, INC., OF BRIDGEPORT, CONNECTICUT, A CORPORATION OF NEW YORK

DESIGN FOR AN ATTACHMENT PLUG RECEPTACLE

Application filed October 1, 1932. Serial No. 45,187. Term of patent 3½ years.

To all whom it may concern:

Be it known that I, AUGUSTINE H. MASSEY, a citizen of the United States, residing in Stratford, in the county of Fairfield and State of Connecticut, have invented a new, original, and ornamental Design for an Attachment Plug Receptacle, of which the following is a specification, reference being had to the accompanying drawing, forming a part thereof.

Fig. 1 is a front elevational view of the attachment plug receptacle.

Fig. 2 is a side elevational view of the same; and

Fig. 3 is an end view thereof.

I claim:

The ornamental design for an attachment plug receptacle, substantially as shown.

AUGUSTINE H. MASSEY.
